ADJUSTABLE RANGE REFERENCE
SIGNAL CIRCUIT

Harry L. Latham, Jr., Philadelphia, Pa., assignor to
Honeywell Inc., a corporation of Delaware
Filed Dec. 21, 1962, Ser. No. 246,579
8 Claims. (Cl. 323—79)

This invention relates to electrical apparatus and, more particularly to a reference signal range changing circuit.

In the art relating to electronic industrial control systems there is frequently provided a source of reference signals against which other signals may be compared. It is desirable that the reference source be adjustable to provide a predetermined but variable reference signal against which the other signal may be compared. It is also desirable that the adjustability of the reference source signals be such that the signals are variable in a plurality of step-wise range increments and, further, be continuously variable within each of the range increments.

It is accordingly an object of the present invention to provide an improved reference signal circuit which is adjustable in a plurality of incremental ranges and, further, is continuously adjustable within each of said ranges.

It is a further object of the present invention to provide a reference signal source circuit which is characterized in an avoidance of discontinuities or providing a "bumpless" transition between successive ranges.

It is a further object of the present invention to provide an improved reference signal source circuit as set forth which is further characterized in that the bumpless transition between successive ranges is operative whether the circuit is being adjusted to provide for an increasing reference signal or decreasing reference signal.

In accomplishing these and other objects there has been provided, in accordance with the present invention, an improved reference signal source wherein a plurality of range determining resistors are serially connected across the output terminals of a regulated power supply. A switching arrangement is provided for switching between successive ranges represented by the serially connected range resistors. There is also provided a slide-wire arrangement for continuously adjusting the magnitude of the reference signal within each of the selective ranges. The range switching elements are so arranged that between each of the operating range positions on the switched elements there is provided a hold position which provides a by-pass for the slide-wire adjustment. This permits the slide-wire to be returned to its initial position before adjusting the range switch to the next operating range position. This arrangement obviates the discontinuity in the developed reference output signal which would otherwise be produced by switching to the next range position of the switches while the slide-wire element is at the upper limit of its travel.

A better understanding of this invention may be had from the following detailed description when read in connection with the accompanying drawing in which the single figure is a schematic circuit representation of apparatus constructed in accordance with the present invention.

Referring now to the drawing in more detail, there is shown in the single figure a regulated power supply 2 connected to a source of alternating current energy 4. The regulated power supply itself does not form a part of the present invention, and consequently, it is shown in block form. Any one of numerous well-known regulated power supply circuits may be utilized to provide the

2

regulated output signal. In fact, the output of the regulated power supply may be either an alternating current signal or a direct current signal, as desired. The regulated output signal from the power supply circuit 2 is applied between a pair of leads 6 and 8, respectively. Between the leads 6 and 8 there is connected a series array of range-determining resistors 10, 12, 14 and 16, respectively. In the illustrated embodiment of this invention, means are provided for establishing three distinct ranges for the reference signal. In order to establish these ranges a plurality of connections are made to the junctions between the several range determining resistors. For example, a first connecting lead 18 is connected to the junction between resistors 10 and 12, a second connecting lead 20 is connected to the junction between the resistors 12 and 14, and a third connecting lead 22 is connected to the junction between the resistors 14 and 16.

In order to effect the selection between the several ranges there are provided three multi-position switches, 24, 26 and 28, respectively. The first switch 24 is illustrated as having five fixed contacts 24a-e and a movable contact 24f. Similarly, the second switch 26 is illustrated as having five fixed contacts 26a-e and a movable contact 26f. Again, the third switch 28 is shown as having five fixed contacts 28a-e and a movable contact 28f. The movable contact members of these three switches are interconnected or ganged together for simultaneous operation between successive contact points. This interconnection is represented in the drawing by the dotted line 30.

The first two fixed contacts 24a and 24b of the switch 24 are connected together and to the connecting lead 18. The connecting lead 18 is, in turn, connected to the junction between the range determining resistors 10 and 12. The third and fourth contacts 24c and 24d of the switch 24 are connected together and to the connecting lead 20 which is, in turn, connected to the junction between the range determining resistors 12 and 14. The fifth contact 24e of the switch 24 is connected to the connecting lead 22 which is, in turn, connected to the junction between the range determining resistors 14 and 16. The first and second fixed contacts 26a and 26b of the second switch 26 are connected together and to the connecting lead 20. The third and fourth fixed contacts 26c and 26d of the switch 26 are connected together and to the connecting lead 22. The fifth contact 26e of the switch 26 is connected directly to the lead 8. The movable contact 24f of the switch 24 is connected to one end of the terminal of a slide-wire resistor 32. The movable contact 26f of the switch 26 is connected to the opposite end terminal of the slide-wire resistor 32. In the third switch 28 the first fixed contact 28a, the third fixed contact 28c, and the fifth fixed contact 28e are connected together and to the slider 34 which, in turn, operates along the slide-wire resistor 32. The second fixed contact 28b and the fourth fixed contact 28d of the switch 28 are connected together and to the movable contact 26f of the switch 26. The movable contact 28f of the switch 28 is connected to an output voltage dividing circuit including a first resistor 36 and a second resistor 38 connected in series, the lower end of the resistor 38 being connected to the lead 8. A pair of output terminals 40 and 42 are connected, respectively, to opposite ends of the resistor 38.

In operation the regulated power supply 2 may be selected to provide any predetermined output voltage desired across the leads 6 and 8. Typically this voltage may be on the order of 6.3 volts. This voltage is then applied across the series string of the range determining resistors 10, 12, 14 and 16. If the resistors 10, 12, 14

and 16 are of equal value, then the applied voltage will be uniformly divided and the corresponding sub-multiple of the applied voltage would appear at each of the junctions between the aforesaid range determining resistors. If on the other hand, it is deemed desirable to provide unequal sub-divisions of the applied voltage at the several junctions, then, of course, the relative values of the range determining resistors may be of unequal value. For the sake of simplicity in description it will be assumed that the resistors 10, 12, 14 and 16 are of equal value. With this arrangement it may be seen, assuming the aforementioned output voltage from the regulated power supply 2, that slightly less than 1.6 volts will be developed across each of the 4 resistors. Initially let it be assumed that the movable contact on each of the three switches 24, 26 and 28 is at its lower most position—that is, in engagement with the corresponding fixed contact *e* in each of the switches. Let it further be assumed that the slider 34 on the slidewire 32 is at its lower most position as viewed in the drawing. Under these conditions the contact 24*f* of the switch 24 is connected through the fixed contact 24*e* to the lead 22. This lead, in turn, is connected to the junction between resistors 14 and 16. The movable contact 26*f* is connected through the fixed contact 26*e* to the system common lead 8. With the switches 24 and 26 thus positioned, the difference in potential between the common lead 8 and the connecting lead 22 is applied across the end terminals of the slidewire resistor 32. With the slider 34 at the lowest end of the slidewire resistor 32 the potential on the slider 34 will be zero with respect to the common lead 8. The movable contact 28*f* of the switch 28 is connected through the fixed contact 28*e* to the slider 34. Thus, under these conditions, the potential across the voltage dividing resistors 36 and 38 is zero, as is the potential across the output terminals 40 and 42. With the switches 24, 26 and 28 remaining in the stated position, it may be seen that as the slider 34 is moved along the slidewire resistor 32 towards the upper end thereof, the potential across the voltage dividing resistors 36 and 38 is increased up to the maximum of the potential developed across the resistor 16 in the range determining combination. As the potential across the voltage dividing resistors 36 and 38 goes up the portion developed across the resistor 38 similarly increases. The purpose of the voltage dividing resistors 36 and 38 is to permit the selecting elements of the circuit to be operated at such a higher voltage level that the significance of contact and thermal potentials developed therein is obviated, while yet permitting the output voltage across the terminals 40 and 42 to be relatively small, for example in the millivolt range. To accomplish this, it may be readily apparent that the resistor 36 might well be relatively large as compared to the resistor 38.

When the slider 34 has reached the upper limit of the slidewire resistor 32, in order to further increase the output or reference signal, it becomes necessary to actuate the switches to introduce the second range of signals. Accordingly, the switches 24, 26 and 28 are actuated to move the movable elements thereof to the next fixed contact. Thus, the movable element 24*f* will be in engagement with the fixed contact 24*d* of the switch 24, the movable contact 26*f* will be in engagement with the fixed contact 26*d* of the switch 26 and the movable contact 28*f* will be in engagement with the fixed contact 28*d* of the switch 28. With the switches in this position, the movable contact 24*f* of the switch 24 is connected to the lead 20 which is, in turn, connected to the junction between the range determining resistors 12 and 14. The movable contacts 26*f* of the switch 26 is connected to the lead 22 which is, in turn, connected to the junction between the range determining resistors 14 and 16. In this position the potential developed across the range determining resistor 14 is applied across the slidewire resistor 32 and the potential developed across the range determining resistor 16 is applied between the lower terminal of the slide-

wire resistor 32 and the common lead 8. Inasmuch as the movable contact 28*f* of the switch 28 is connected, through the fixed contact 28*d*, to the lower end of the slidewire resistor 32, the potential developed across the range determining resistor 16 is thereby applied across the voltage dividing resistors 36 and 38. This potential is identical to the potential applied across the resistors 36 and 38 when the three switches were connected in their lowermost position and the slider 34 was at the upper limit of its travel along the slidewire 32. In this position it will be noted that no connection is made to the slider 34. Thus, the slider 34 may be moved along the slidewire 32 without influencing the potential across the voltage dividing resistors 36 and 38, hence, without influencing the output potential across the terminals 40 and 42. Under these conditions the slider 34 may be returned to the lower end of the slidewire 32 in readiness for an adjustment of the output potential through the middle range of signals.

When the slider 34 has been returned to the lowermost position along the slidewire 32 the switches 24, 26, and 28 may then be moved to the next successive position, that is, to the fixed contact *c* of each of the switches. Because of the particular interconnection of the fixed contacts of the switches 24 and 26, no change in the potentials applied to the movable contacts 24*f* and 26*f* results as a function of the transfer from the *d* position to the *c* position. That is, the potential developed across the range determining resistor 16 is applied between the lower end of the slidewire resistor 32 and the common lead 8. Similarly, the potential developed across the range determining resistor 14 is applied across the terminals of the slidewire resistor 32. With the slider 34 at the lower extremity of the slidewire 32 the potential applied across the two voltage dividing resistors 36 and 38 hence the two output terminals 40 and 42 is unchanged as a result of the transfer of the movable contacts of the switches 24, 26 and 28 to the *c* position of each of the switches, respectively. The only change that has taken place as a result of that transfer is that the movable contact 28*f* of the switch 28 is connected, through the *c* contact, to the slider 34 on the slidewire 32. With the switches in this position the slider 34 may now be advanced toward the upper end of the slidewire 32 producing a progressive increase in the potential applied across the two voltage dividing resistors 36 and 38 until the slider 34 has reached the upper limit of the slidewire 32. At that point the potential across the two voltage dividing resistors 36 and 38 is equal to the sum of the potentials across the two range determining resistors 14 and 16.

When the slider 34 has again reached the upper limit of the slidewire resistor 32, in order to still further increase the output or reference signal, it becomes necessary to again actuate the switches to introduce the next range of signals. As before the switches 24, 26 and 28 are actuated to move the movable elements thereof to the next fixed contact. Thus the movable contact 24*f* will be in engagement with the fixed contact 24*b*, the movable 26*f* will be in contact with the fixed contact 26*b*, and the movable contact 28*f* will be in engagement with the fixed contact 28*b*. With the switches in this position, the movable contact 24*f* of the switch 24 is connected to the lead 18 which is, in turn, connected to the junction between the range determining resistors 10 and 12. The movable contact 26*f* of the switch 26 is connected to the lead 20 which is, in turn, connected to the junction between the range determining resistors 12 and 14. In this position, the potential developed across the range determining resistor 12 is applied across the slidewire resistor 32 and the sum of the potential developed across the range determining resistors 14 and 16 is applied between the lower terminal of the slidewire resistor 32 and the common lead 8. Again, since the movable contact 28*f* of the switch 28 is connected, through

fixed contacts 28b, to the lower end of the slidewire resistor 32, the sum of the potential developed across the range determining resistors 14 and 16 is thereby applied across the voltage dividing resistors 36 and 38. This potential is identical to the potential applied across the resistors 36 and 38 when the movable contacts of the three switches were engaged with the fixed contact c of each of the switches, respectively and the slider 34 was at the upper limit of its travel along the slidewire 32. As before, in this position there is no connection made to the slider 34. Thus, the slider 34 may be moved along the slidewire 32 without influencing the potential established across the voltage dividing resistors 36 and 38, hence without influencing the output potential across the terminals 40 and 42. Here, too, the slider 34 may be returned to the lower end of the slidewire 32 in readiness for an adjustment of the output potential through the upper range of signals.

When the slider 34 has been returned to the lowermost position along with slidewire 32, the switches 24, 26 and 28 may then be moved to the upper most position, that is, to the fixed contact a of each of the switches, respectively. Here again, because of the particular interconnection of the fixed contacts of the switches 24 and 26, no change in the potentials applied to the movable contacts 24f and 26f result as a function of the transfer from the b position to the a position. That is, the potential developed across the range determining resistors 14 and 16 is applied between the lower end of the slidewire resistor 32 and the common lead 8. Similarly, the potential developed across determining resistor 12 is applied across the terminals of the slidewire resistor 32. With the slider 34 at the lower extremity of the slidewire 32, the potential applied across the two voltage dividing resistors 36 and 38, hence, the two output terminals are 40 and 42 is then changed as a result of the transfer of the movable contacts of the switches 24, 26 and 28 to the a position of each of the switches, respectively. Again, the only change that has taken place as a result of that transfer is that the movable contact 28f of the switch 28 is connected, through the a contact, to the slider 34 of the slidewire 32. With the switches in that position, the slider 34 may again be advanced toward the upper end of the slidewire 32 producing a progressive increase in the potential applied across the two voltage dividing resistors 36 and 38 until the slider 34 has reached the upper limit of the slidewire 32. At that point the potential across the two voltage dividing resistors 36 and 38 is equal to the sum of the potentials across the three range determining resistors 12, 14 and 16. That signal is then the maximum signal obtainable with the illustrated circuit.

In the circuit and operation thus far described it may be seen that the second and fourth switch positions, that is the positions indicated by the fixed contacts b and d, respectively are hold positions whereby the output of the system is independent of the position of the slider 34 along the slidewire resistor 32 whereby the slider 34 may be returned to its standing position between range changes without producing a so-called "bump" or discontinuity in the progressively adjustabel output signal.

It will also be appreciated from an examination of the illustrated embodiment of the invention that the continuous adjustability of the system is equally operable in the reverse direction, that is, starting with the maximum signal, the signal may be progressively decreased through the several ranges with the intermediate hold positions as before.

What is claimed is:

1. An adjustable reference signal circuit comprising a power supply circuit having a pair of output leads, a plurality of range determining resistors connected in series between said leads, an adjustable potentiometer having a slidewire resistor and a slider, first switch means for selectively connecting said slidewire resistor across a selected

one of said range determining resistors and having a plurality of pairs of switch positions each of which pairs is individual to a different signal range, an output circuit, a further switch means connected between said first switch means and said output circuit, said further switch means including two sets of fixed contacts arranged alternately, one set of said fixed contacts being connected to said slider, the other set of said fixed contacts being connected to said first switch means whereby to by-pass said potentiometer when said further switch means is closed on said other set of fixed contacts on alternate positions of said further switch means, and means for ganging said further switch means to said first switch means to cause said further switch means to close on a contact of said one set when said first switch means has one of the positions of each of said pairs of positions, and to close on a contact of said other set when said first switch means has the other of the positions of each of said pairs of positions, said alternate positions of said further switch means at which the latter is closed on said other set of contacts comprising hold positions between range changes whereat said slider may be returned to a starting position on said slidewire resistor without affecting an output signal on said output circuit.

2. An adjustable reference signal circuit comprising a power supply circuit having a pair of output leads, a plurality of range determining resistors connected in series between said leads, an adjustable potentiometer having a slidewire resistor and a slider, first switch means having a plurality of switch positions for selectively connecting said slidewire resistor across a selected one of said range determining resistors, an output circuit, and a second switch means having a plurality of switch positions corresponding in number to the number of switch positions of said first switch means, said second switch means having a first set of switch positions whereat said slider is connected to said output circuit, said second switch means having a second set of switch positions arranged intermediate said first switch positions of said second switch means whereat said output circuit is connected to said first switch means by-passing said potentiometer, said plurality of switch positions of said first switch means including a first switch position representative of a first signal range, the remainder of said plurality of switch positions of said first switch means being grouped in pairs of switch positions, and each of said pairs of switch positions being representative of a different signal range, said first switch means and said second switch means being ganged together for conjoint operation, said intermediate switch positions of said second switch means and the corresponding switch positions of said first switch means constituting hold positions whereat said slider may be returned to a starting position on said slidewire resistor without affecting the signal on said output circuit determined by the switch position of said first switch means relative to said range resistors.

3. An adjustable reference signal circuit comprising a power supply circuit having a pair of output leads, a plurality of range determining resistors connected in series between said leads, an adjustable potentiometer having a slidewire resistor and a slider, first switch means having a plurality of switch positions for selectively connecting said slidewire resistor across a selected one of said range determining resistors, an output circuit having a pair of leads one of which is connected to a corresponding one of said power supply output leads, and second switch means having a plurality of switch positions corresponding in number to the number of switch position of said first switch means, said second switch means having a first set of switch positions whereat said slider is connected to said output circuit, said second switch means having a second set of switch positions arranged intermediate said first switch positions of said second switch means whereat said output circuit is connected to said first switch means bypassing said potentiometer, said plurality of switch positions of said first switch means including a first switch

position representative of a first signal range, the remainder of said plurality of switch positions of said first switch means being grouped in pairs of switch positions, and successive one of said pairs of switch positions being representative of successive signal ranges, said first switch means and said second switch means being ganged together for conjoint operation, said intermediate switch positions of said second switch means and the corresponding switch positions of said first switch means constituting hold positions whereat said slider may be returned to a starting position on said slidewire resistor without affecting the signal on said output circuit determined by the switch position of said first switch means relative to said range resistors.

4. The invention as set forth in claim 3 wherein said first switch means includes a first switch member and a second switch member, each of said switch members including a plurality of fixed contacts corresponding in number to said plurality of switch positions, each of said switch members having a movable contact, said movable contact of said first switch member being connected to one end of said slidewire resistor, and said movable contact of said second switch member being connected to the opposite end of said slidewire resistor.

5. The invention as set forth in claim 4 wherein said second set of switch positions of said second switch means is connected to the movable contact of said second switch member of said first switch means.

6. The invention as set forth in claim 3 wherein said output circuit includes voltage dividing resistors to substantially reduce the magnitude of the output signal.

7. An adjustable reference signal circuit comprising a power supply circuit having a first and a second output lead, a plurality of range determining resistors connected in series between said leads, an adjustable potentiometer having a slidewire resistor and a slider, first switch means having a plurality of switch positions for selectively connecting said slidewire resistor across a selected one of said range determining resistors said first switch means including a first switch member and a second switch member, said first and second switch members each having a movable contact and a plurality of fixed contacts corresponding in number to said plurality of switch positions of said first switch means, means connecting said movable contact of said first switch member to one end of said slidewire resistor, means connecting said movable contact of said second switch member to the opposite end of said slidewire resistor, means connecting a fixed contact of said second switch member to said second output lead, the remainder of said fixed contacts of said second switch member being connected in pairs, means connecting successive pairs of said fixed contacts of said second switch member to successive junctions between said range determining resistors, respectively, means connecting a first fixed contact of said first switch member to the junction between a first and a second one of said range determining resistors, the remainder of said fixed contacts of said first switch member being connected in pairs, means connecting successive pairs of said fixed contacts of said first switch member to successive junctions between said range determining resistors, respectively, subsequent to said junction to which said first fixed contact of said first switch member is connected, an output circuit, a second switch means including a further switch member having a movable contact and a plurality of fixed contacts corresponding in number to the number of switch positions of said

5 first switch means, means connecting alternate ones of said fixed contacts of said further switch member together and to said slider, means connecting the fixed contacts of said further switch member intermediate said alternate contacts together and to the movable contact of said second switch member, and means connecting said movable contact of said further switch member to said output circuit.

8. An adjustable reference signal circuit comprising a power supply circuit having a first and a second output lead, a plurality of range determining resistors connected in series between said leads, an adjustable potentiometer having a slidewire resistor and a slider, first switch means having a plurality of switch positions for selectively connecting said slidewire resistor across a selected one of said range determining resistors, said first switch means including a first switch member and a second switch member, said first and said second switch members each having a movable contact and a plurality of fixed contacts corresponding in number to said plurality of switch positions of said first switch means, means connecting said movable contact of said first switch member to one end of said slidewire resistor, means connecting said movable contact of said second switch member to the opposite end of said slidewire resistor, means connecting a fixed contact of said second switch member to said second output lead, the remainder of said fixed contacts of said second switch member being connected in pairs, means connecting successive pairs of said fixed contacts of said second switch member to successive junctions between said range determining resistors, respectively, means connecting a first fixed contact of said first switch member to the junction between a first and a second one of said range determining resistors, the remainder of said fixed contacts of said first switch member being connected in pairs, means connecting successive pairs of said fixed contacts of said first switch member to successive junctions between said range determining resistors, respectively, subsequent to said junction to which said first fixed contact of said first switch member is connected, an output circuit, a second switch means including a further switch member having a movable contact and a plurality of fixed contacts corresponding in number to the number of switch positions of said first switch means, means connecting alternate ones of said fixed contacts of said further switch member together and to said slider, means connecting the fixed contacts of said further switch member intermediate said alternate contacts together and to the movable contact of said second switch member, and means connecting said movable contact of said further switch member to said output circuit, said output circuit including voltage dividing resistors to substantially reduce the magnitude of the output signal.
